[57] CLAIM

The ornamental design for a projection television receiver, substantially as shown and described.

DESCRIPTION

FIG. 1 is a front, top and partial left side perspective view of a projection television receiver showing our new design;

FIG. 2 is a right side elevational view, the left side being substantially a mirror image thereof;

FIG. 3 is a rear elevational view;

FIG. 4 is a front elevational view; and

FIG. 5 is a top plan view.
